UNITED STATES PATENT OFFICE

CHARLES E. CONSTABLE, OF CINCINNATI, OHIO, ASSIGNOR TO THE NATIONAL MARKING MACHINE COMPANY, OF CINCINNATI, OHIO, A CORPORATION OF OHIO

SPIRAL CONVEYER DEVICE FOR PACKAGES AND COAT HANGERS

Application filed June 4, 1929. Serial No. 368,334.

My device is especially adapted for use in connection with laundry and dry cleaning establishments, and is for the purpose of conveying laundry packages from an upper floor 5 to a lower one, and at the same time conveying garments upon coat hangers, said conveyer devices being designed to utilize the same space.

The object of my invention is to provide 10 a coat hanger attachment for spiral conveyers, so constructed and arranged that articles supported upon coat hangers may be received upon an upper floor and delivered to a lower floor, and during their movement will 15 occupy only the space between the various portions of the spiral package conveyer.

A further object is to provide a coat hanger conveyer device of this character supported at its upper end above the package 20 conveyer, and supported at its lower end above the lower end of the package conveyer, and firmly fixed to the outer edge of the package conveyer, and whereby the two conveyers will mutually support and brace each other.

My invention consists in the construction of 25 the spiral coat hanger conveyer, and its arrangement and combination with the package conveyer, whereby the objects contemplated are attained, as hereinafter more fully set forth, pointed out in my claims, and illustrated in the accompanying drawings, in which:

Figure 1 shows a side elevation of a package conveyer having my improved coat hanger conveyer applied thereto; and

Figure 2 shows an enlarged detail view 30 showing a portion of the package conveyer in vertical transverse section supported upon a post, and having my improved coat hanger conveyer rigidly connected therewith, and illustrating a coat hanger mounted on the coat hanger conveyer.

Referring to the accompanying drawings, I have used the numeral 10 to indicate an 35 upright post for supporting the combined conveyers. The spiral package conveyer comprises a sheet metal bottom member 11, and a sheet metal outer side wall 12. The outer edge of the bottom member 11 is inclined downwardly at 13 and connected at its

lower end with the side member 12 by bolts 14. The receiving end of the conveyer is preferably spaced above an upper floor 15, and the lower delivery end is preferably spaced above a lower floor to discharge its contents 55 upon a table 16 or the like.

The construction of the spiral package conveyer is the same as those now in ordinary use.

My improved coat hanger spiral conveyer 60 attachment comprises a spiral track 17 having its upper end projecting above the receiving end of the spiral package conveyer and supported by brackets 18 on the upright post 10. This upper end is spaced apart 65 from the upper end of the package conveyer far enough to permit a garment 19 supported on a coat hanger 20 to clear the package conveyer.

The body portion of the coat hanger conveyer is supported upon brackets 21, which brackets are preferably secured to the package conveyer by means of bolts 14. This spiral coat hanger conveyer is supported by its brackets 21 directly beneath the lower 75 outer edge of the package conveyer, so that garments carried thereby will, throughout their entire path of travel, descend in a position directly above the wall of the spiral package conveyer. 80

At its lower end this spiral coat hanger conveyer is extended radially away from the package conveyer at 22, and its end is supported upon a post 23 or the like, and is elevated far enough above the lower floor to 85 permit a garment to hang clear of the floor, as shown in Figure 1.

By means of my improved construction, and in view of the fact that the coat hanger conveyer is rigidly supported at both its upper and lower ends independently of the package conveyer, and in view of the fact that the coat hanger conveyer is made of a rigid rail construction, it will be seen that the two conveyer devices, being connected by 90 the brackets 21, will mutually brace and support each other. 95

It will also be seen that the space occupied by the coat hanger conveyer is space that would otherwise be wasted, as it is principal 100

ly between the various courses of the spiral package conveyer.

It will also be seen that movement of the coat hangers with garments attached thereto, and the movement of the packages upon the spiral package conveyer, will not in any way interfere with each other, and may be carried on either simultaneously or independently.

I claim as my invention:

- 10 1. The combination of a spiral package
conveyer and a coat hanger conveyer having
its upper end spaced considerably above the
upper end of the spiral package conveyer,
and having its body portion supported be-
neath the body portion of the spiral package
conveyer, and having its lower end extended
15 radially outwardly from the spiral package
conveyer, whereby articles mounted on coat
hangers may move downwardly on the spiral
20 coat hanger conveyer without interfering
with the movement of the packages upon the
spiral package conveyer, the upper and lower
ends of the spiral coat hanger conveyer be-
ing secured to fixed supports, and the body
25 portion of the spiral conveyer being rigidly
secured to the under portion of the spiral
package conveyer, whereby said conveyers
mutually brace and support each other.

20 2. The combination of a spiral package
conveyer and a coat hanger conveyer having
its upper end spaced considerably above the
upper end of the spiral package conveyer,
and having its body portion supported be-
neath the body portion of the spiral package
35 conveyer, and having its lower end extended
radially outwardly from the spiral package
conveyer, and whereby articles mounted on
coat hangers may move downwardly on the
spiral coat hanger conveyer without inter-
40 fering with the movement of the packages
upon the spiral package conveyer, said spiral
package conveyer being formed with a down-
wardly extending flange at its outer edge,
bolts for connecting said flange to the side
45 of the package conveyer, and brackets con-
nected to said bolts for supporting the body
portion of the coat hanger conveyer.

Des Moines, Iowa, May 9, 1929.
